UNITED STATES PATENT OFFICE.

WILLIAM A. SAWYER, OF BRIDGEWATER, NEW HAMPSHIRE, ASSIGNOR TO
THE METROPOLITAN ELEVATOR COMPANY, OF PORTLAND, MAINE.

STREET-SWEEPER.

SPECIFICATION forming part of Letters Patent No. 426,073, dated April 22, 1890.

Application filed January 6, 1890. Serial No. 336,063. (No model.)

To all whom it may concern:

Be it known that I, WILLIAM A. SAWYER, a citizen of the United States, residing at Bridgewater, in the county of Grafton and State of New Hampshire, have invented certain new and useful Improvements in Street-Sweepers, of which the following is a full specification.

My invention consists of an improved street-sweeping and elevating apparatus adapted to be readily attached to any ordinary cart to be operated thereby as the cart moves along, the construction being as hereinafter described.

In the accompanying drawings, Figure 1 is a side elevation of my improved apparatus attached to an ordinary street-cart. Fig. 2 is a detail view showing the operation of the universal joint on the friction-pulley shaft. Fig. 3 is a plan view of the apparatus and cart with the brush removed to show parts lying beneath. Fig. 4 is a plan view of the brush-frame. Fig. 5 is a section on $z z$, Fig. 3, through the street-sweeper detached. Fig. 6 is an elevation of the apparatus, partly broken away, showing the side opposite to that shown in Fig. 1. Fig. 7 is a side view of one of the band-stays. Fig. 8 shows in section, on an enlarged scale, the relative position of elevating bands, chains, and stays; and Fig. 9 is a section, on an enlarged scale, through the hub of the wheel and the flanged nut for attaching the sweeper-frame. Fig. 10 is a perspective sectional view on an enlarged scale, showing the construction and arrangement of the contiguously movable elevator bands and chains. Fig. 11 is an enlarged rear view, partly in section, showing one side of the frame, one of the inclined fenders secured thereto, and adjacent parts; and Fig. 12 is a perspective view of one of the fenders.

The working parts of the sweeper are supported by the frame $A A' A^2 A^3$, formed of similar pieces on each side. Of these the forwardly-projecting arms A^3 connect the sweeper with the cart in the manner presently to be described, while the rear of the sweeper rests upon the wheels M , connected with the rear of the bars A^2 on each side.

50 Mounted in suitable bearings H^3 on the

arms A^2 is the shaft h of the brush-frame, which bears the bundles of splints H' , forming the brush. These splint bundles are adjustable in such a manner that both the diameter of the brush and the stiffness of the splints may always be kept the same in spite of the wearing away of the brush. The circular end pieces H of the brush-frame are provided with the inner flanges h^5 .

h' are radially-movable cross-pieces tapped near each end thereof to admit the screws h^2 , whose inner ends are seated in or against the shaft h , while their heads are in the flanges h^5 , as shown in Figs. 4 and 5, the construction being such that by turning the screws h^2 at each end of the cross-pieces h' the said pieces are radially movable in and out at will.

h^3 are rods arranged in pairs crossing from one side to the other of the frame between the flanges h^5 , and between each pair of rods passes a row of splint bundles H' , the inner ends of these bundles being secured to the sliding pieces h' , while the bundles themselves pass through the spaces h^6 , Fig. 4, between the wires h^4 and the rods h^3 . By this arrangement the working ends of the brush-bundles may be kept always of the same stiffness and length, and the diameter of the brush kept constant in spite of the wear, by turning the screws h^2 from time to time, and thus sliding out the bundles. The brush revolves in the direction indicated by the arrow and sweeps up the dirt and rubbish over the dust-pan J to the elevator.

J' is a cross-piece passing between the arms A^2 and secured to the under sides thereof. To this cross-piece is bolted the metal support j , (see Fig. 5,) near the top of which is attached the continuous strip of leather j' . (See also Fig. 3.)

J are a number of curved sections forming the dust-pan, each being independently fastened to the leather strip j' , so that they have a pivotal movement over stones and obstacles as the cart is moved along. These sections J are wider at the bottom than at the top, being arranged so that they nearly but not quite touch each other at the bottom, the spaces between them growing gradually wider toward the top, as seen in Fig. 3, so that

as the brush revolves the splints cannot be caught or wedged between the sections of the pan, but always run free. Each section J is preferably re-enforced along its bottom with the rod j^3 , riveted or otherwise secured thereto, as shown in Fig. 11, and so placed as to receive the wear as the various sections move along the ground.

From the dust-pan the dirt is carried direct to the elevator, which will next be described. In the two sides of the frame are held the numerous shafts or spindles $ff'f^2f^3d^2d^3$, on which are mounted in pairs the sprocket-wheels $F F' F^2 F^3$ and pulleys $D D^2 D^3$, the two wheels or pulleys constituting each pair being similarly mounted on its spindle, one near each side of the frame. Over these wheels and pulleys run the endless elevator-chains $C C'$, which are bound along the edges of two elevator-bands $B B'$, made of canvas or any suitable flexible material, arranged as shown in Figs. 3 and 5, the pair of chains $C C'$ being secured to the edges of the endless band B , while the pair of chains $C' C'$ are secured to the edges of the endless band B' . The position of the wheels and pulleys is such that the two bands through a portion of their path move contiguously one above the other, the faces of the various sprocket-wheels and pulleys being of sufficient width to carry the chains only while the bands which are secured to each pair of chains along their edges are hung between these chains. The pair of chains C , secured to the edges of the band B , one on each side, run around the sprocket-wheels and pulleys $F F' D D^2 D^3$ (see Fig. 5,) while the pair of chains C' , secured along the edges of the band B' , run around the pairs of sprocket-wheels $F^3 F'$ and the pulleys D , the arrangement being such that on each side of the bands the chains C' and C move contiguously, one above the other, between the pulleys D and the sprocket-wheels F' , the chains and bands moving in the direction indicated by the arrows. At regular intervals between corresponding links of each pair of chains run stays $b b'$, which preferably consist of wooden strips of the shape shown in Fig. 7, being thickest in the middle and tapering toward both ends. The ends of these stays are attached by riveting or otherwise to ears $c c'$ on the inside of the links of both chains, as indicated in Figs. 3 and 5, the ears serving also as a means for securing the bands to the chains. These stays serve to hold the dirt and rubbish between the elevator-bands during the elevating portion of their path, and to this end are arranged with the flat surface outward, while the convex surface is next to the band, as shown in Figs. 8 and 10, the bands being riveted or otherwise secured to the stays. I prefer to so arrange the stays that through that portion of the path of the two bands where they move contiguously—*i.e.*, through the elevating portion—the stays b' on the band B' are slightly in advance of the stays b on the

band B , and since the increased thickening of the material of the stay comes on the inside altogether—*i.e.*, on the side next the band—and since the chains C and C' are in contact, it follows that as the belts come together and move contiguously upward during the elevating portion the two bands will assume along their center a somewhat zigzag shape, similar to that shown in Figs. 5 and 10, the natural sagging of the bands between the stays being to some extent taken up by the bulging shape of the stays, the dirt and rubbish being thus securely held between the bands. The band B has at the bottom and top the receiving and delivering portions $b^2 b^3$, respectively, which preferably move horizontally, the dirt being directly swept from the pan J upon the receiving-apron b^2 , formed by the lower portion of the band B . To keep the band B practically tangential to the dust-pan through its entire width, I employ the roller O , mounted on the same spindle f^2 as the sprocket-wheels F^2 , and turning therewith and occupying the space between the two sprocket-wheels F^2 of the pair. This roller O is provided with a longitudinal groove o , Fig. 5, along its face of a size sufficient to contain a stay b within it, and the circumference of the roller is preferably just equal to the distance between the stays, so that as each stay b comes to the roller in the course of its journey it engages with the groove o , thus presenting a smooth outer surface at all times to the top of the dust-pan along its full length as the band moves around the roller. From the receiving-apron b^2 the dirt is carried up by the contiguously-moving bands, in the manner previously described, being finally carried along the delivering-apron b^3 and discharged into the body W of the cart, it being understood that all portions of the band B act successively as the receiving-apron, the elevating portion, and the delivery-apron. The ends of the spindles f^3 and f , on which are mounted the sprocket-wheels F^3 and F at the upper ends of the elevator-bands, are held in movable boxes $I^2 I^3$, which slide in slots $a a'$, respectively, in the two sides of the frame, their position being controlled by the screws $I I'$. In this manner the tension of the elevator-band chains may be readily adjusted.

The street-sweeper is attached to the cart by connecting the arms A^3 to extensions of the axle beyond the hubs of the wheels, this being the only connection, and the various working parts are operated by frictional gearing with the cart-wheels in a somewhat similar manner to that shown and described in my application for United States Letters Patent for an improved street-sweeper, filed April 27, 1889, serial No. 308,868. The hubs W^2 of the wheels W' are held on the cart-axes w by means of the axle-nuts U' , which instead of having square or hexagonal heads, as ordinarily, have circular heads provided with exterior screw-threads, on which screw

the flanged attaching-nuts U in the manner shown in Fig. 9. These attaching-nuts U are provided with flanges u u', which project beyond the wheel-hubs and embrace the material of the projecting arms A³, the slots a³ in which are adapted to fit over the said attaching-nuts in a manner easily understood by reference to Figs. 1 and 9. The distance between the two arms A³ is such that they pass outside the hubs of the wheels on each side, and engage with the attaching-nuts U in the manner described, being clamped when in place by the screws or bolts a², the inner ends of which are preferably provided with elastic cushions a⁴, which are interposed between the end of the bolts and the material of the attaching-nuts in such a manner as to lessen the jarring effect of the sweeper. The extensions of the cart-axle nuts are thus the only points of attachment of the sweeper-frame. These extensions or flanged attaching-nuts U may be unscrewed at any time, when desired, from the axle-nuts U', so that the cart may be used irrespective of the sweeper and without having any projections beyond the wheel-hubs.

E E are friction-wheels mounted to turn loosely on the shaft e, which is journaled in the two sides of the sweeper-frame. These wheels are situated in proper position laterally to engage by frictional contact with the tires of the cart-wheels W', being preferably provided for this purpose with the rubber rims e'. All the moving parts of the sweeper are actuated through the shaft e, which can be turned only in one direction. To this end the hub of each wheel E has attached thereto the pawl G, (see Fig. 5,) which engages with the ratchet-wheel G', fixed on the shaft e, the pawl being kept in engagement with the teeth of the ratchet by means of the spring g, the ratchet-teeth being so pointed that when the cart is moving forward the shaft e is turned in the proper direction through the engagement of the wheel W' with the friction-wheel E. When, however, the cart is backed, or by the shying of the horse either of the cart-wheels is turned in the reverse direction, the friction-wheel engaging therewith, which of course is reversed, does not act to turn the shaft e, but the pawl simply slips along the teeth of the ratchet G', so that when the cart is backed none of the mechanism is moved.

Fixed on the shaft e to turn therewith is the sprocket-wheel N³, outside the frame, Fig. 6, which, through the chain L² and the exterior sprocket-wheels N² and N, fixed on the elevator-spindles f' and f², respectively, give motion to the elevator chains and bands. On the opposite side of the frame to the exterior sprocket-wheel N³ is fixed on the same shaft e the sprocket-wheel E', which, through the chain L and the second sprocket L³, mounted fast on the brush-shaft h, gives motion to the brush.

The rear of the machine rests upon the cas-

ter-wheels M, the shanks of which are inclined, as shown, and are attached to the rear of the arms A² by means of the plates m and m'.

The height of the rear end of the machine, and hence the pressure of the brush on the ground, may be varied according to the position of the adjustable collar m² on the caster-wheel shank, against which collar the lower plate m' bears.

When the cart, with the sweeper attached, is backed, the rear end of the sweeper is raised by reason of the inclined shanks of the caster-wheels, and the sections J, forming the dust-pan, resting against the cross-piece j², attached to the cross-piece J', are lifted from the ground, thus preventing them from injury.

When the sweeper is removed from the cart, the forward portion thereof is supported by adjustable supports consisting, as here shown, of the screws a⁵, provided with feet at their lower ends and having handles a⁶ at their tops, whereby they may be screwed up or down in the side pieces. When attached to the cart the screws a⁵ are screwed up, as shown in Fig. 1.

The brush-frame and dust-pan, as will be seen by reference to Fig. 3, are much wider than the elevator-bands, being made to sweep as close as possible to the inner sides of the frame.

At each side of the receiving portion b³ of the band B, I employ a guide or fender K', screwed or otherwise secured to the sides of the frame, upon which the dirt swept up by the ends of the brush is carried. The bottom of these guides, as shown in Figs. 11 and 12, are inclined downward and project over the band, so that whatever dirt is swept up on them along the inclined portion k² is sifted down by the jarring action of the sweeper and deposited on the band. At the inner ends of the fenders K' are the fingers k', projecting still farther over the band, which are for the purpose of carrying stones and other large objects down upon the band and preventing them from engaging with and clogging the elevator-chains.

As the wheels of ordinary refuse-carts are dished or inclined inward so that the rims of the two wheels are nearer together at the bottom than at the top, I sometimes employ the arrangement shown in Fig. 2 when the dishing of the cart-wheels is considerable. In this case the two sides A of the frame are connected by the cross-piece A⁴, from the center of which depends the hanger A⁵.

The shaft e of the friction-wheels, instead of passing completely through from side to side, is made in two pieces, each of which is connected by universal joints E² E³, with a short shaft running in a central bearing E⁴, this bearing being preferably provided with a stem or supporting piece e², which may be clamped at varying heights in the hanger A⁵.

to be adjusted to different carts. This allows the friction-wheels to be inclined to correspond with the dishing of the cart-wheels.

When the dishing of the wheels is slight, 5 no universal joint need be employed.

I claim—

1. In a street-sweeper, the combination, with pulleys and sprocket-wheels, of two contiguously-movable flexible endless bands provided with stays to meet in pairs and with 10 endless chains along their edges engaging with said sprocket-wheels and held in suspension between the chains, the said chains moving in surface-contact with each other, substantially as described.

2. In a street-sweeper, two contiguously-movable endless bands provided with endless chains along their edges, having at regular 20 intervals stays arranged to meet in pairs passing across said bands and connecting corresponding links of each pair of said chains, substantially as and for the purposes described.

3. In a street-sweeper, an endless band provided with endless chains bound along its edges and provided at regular intervals with stays passing across said band, connecting 25 corresponding links of said chains, said band having an upwardly-moving elevating portion, in combination with a second endless band similarly provided with chains and stays moving contiguously with the elevating portion of the first and having its stays slightly 30 in advance of those in the first, substantially as and for the purposes described.

4. In a street-sweeper, the combination, with sprocket-wheels and pulleys arranged in pairs, of two contiguously-movable endless bands having endless chains bound along 40 their edges, said chains and bands being provided with dirt-retaining stays, arranged in pairs and operating substantially as and for the purposes described.

5. In a street-sweeper, two contiguously-movable endless bands provided with endless chains along their edges and having stays b b' , thickest in the middle and tapering toward the ends, connecting corresponding links 45

of said chains, substantially as and for the purposes described.

6. In a street-sweeper, the combination, with elevator-bands, of a brush and dust-pan wider than said bands, and fenders K' , provided with inclined portions k^2 on either side of and projecting over said bands, substantially as and for the purposes described.

7. In a street-sweeper, the combination, with elevator bands and chains, of a brush and dust-pan wider than said bands, and sloping fenders K' on either side of said bands, projecting over the same and provided with fingers k' , substantially as and for the purposes described.

8. In a street-sweeper, a dust-pan consisting of a number of curved metal sections J , independently fastened to the continuous leather strip j' , the said sections being wider at the bottom than at the top, substantially as and for the purposes described.

9. The combination, with a dust-pan made in sections independently fastened to a continuous strip of leather, of an elevator-band provided with stays and a longitudinally-grooved roller O at the bottom of the elevator-band, arranged and operating substantially as and for the purposes described.

10. The combination, with a street-sweeper having arms A^3 , provided with fastening-slots, of flanged attaching-nuts U and axle-nuts U' , provided with exterior screw-threads engaging with said attaching-nuts, substantially as described.

11. A street-sweeper provided with elevator and brush driving friction-wheels engaging with the wheels of the cart, to which the 85 sweeper is attached, the said wheels being mounted on shafts connected by universal joints, whereby the said friction-wheels may run at an inclination to each other, substantially as and for the purposes described.

In witness whereof I have hereunto set my hand.

WILLIAM A. SAWYER.
